[57] **CLAIM**

The ornamental design for a bottle, as shown and described.

DESCRIPTION

FIG. 1 is a front elevation of a bottle showing our new design, the appearance of the claimed design repeats five times around the central vertical axis of the bottle;

FIG. 2 is a top plan view thereof; and,

FIG. 3 is a bottom plan view thereof.

The broken lines showing a threaded neck are for illustrative purposes only and do not form part of the claimed design.
